UNITED STATES PATENT OFFICE.

HIRAM H. WALSH, OF NEWBURGH, NEW YORK.

BRICK-DRYING APPARATUS.

SPECIFICATION forming part of Letters Patent No. 732,978, dated July 7, 1903.

Application filed April 20, 1903. Serial No. 153,388. (No model.)

To all whom it may concern:

Be it known that I, HIRAM H. WALSH, a citizen of the United States, residing at the city of Newburgh, in the county of Orange and State of New York, have invented certain new and useful Improvements in Brick-Drying Apparatus; and I do hereby declare the following to be a full, clear, and exact description of the invention, such as will enable others skilled in the art to which it app pertains to make and use the same.

The object of my invention is to provide a new and useful method or process for drying and heating purposes, but especially for drying brick, tile, lumber, &c., which will enable those engaged in the several trades to which it applies to utilize the heat from the boiler and the exhaust-steam from the engine in such a manner that the air in the drier or kiln will be thoroughly heated, and at the same time be pure and free from steam, smoke, or cinders, at a great saving both as to cost of plant and the running expenses thereof.

My invention will be understood by reference to the accompanying drawings, wherein the same parts are designated by the same letters throughout the several views.

Figure 1 is a plan view showing the brick-machine, dump-table, and the arrangement of the boiler, engine, steam-jets, heating-chamber, part of the conduit through which the heated air is forced into the kiln or drier, part of the carrier in the drier, and also the blower by which the air is forced through the tubes in the heating-chamber into the conduit. Fig. 2 is a front elevation of the drier and a transverse vertical section of the heating-chamber on line *xx*, showing the manner in which the heat from the boiler is utilized to heat the tubes in the heating-chamber. Fig. 3 is a longitudinal vertical section of the heating-chamber on the line *YY*, the arrows showing the course of the pure air forced by the blower through the heated tubes in the heating-chamber, where it is heated, into the conduit. Fig. 4 is a view in perspective of a part of the carrier arranged in the drier.

In the drawings, *A* is the boiler; *A'*, the smoke-box, which opens into the heating-chamber *A²*. The hot gases and smoke pass about the tubes *A³* in the chamber *A²* and

out of the stack or chimney *A⁴*, which is provided with a damper *A⁵*.

B is a steam-pipe leading from the boiler *A* into the chamber *A²* and is provided with a valve *B'* near the boiler.

B² is a steam-pipe leading from the boiler *A* into the chamber *D* and is also provided with a valve *B³*.

The exhaust-steam is conducted from the engine *G* into the chamber *A²* through the pipe *B⁴*. The pipe *C* is arranged to pass through the chamber *D* and under the chamber *A²* and the header *D'* and connect with the conduit *E*. In the chamber *D* the pipe *C* is arranged in the form of a *T*, the upper end of which is open. Above the horizontal portion of the pipe *C* is arranged a valve or damper *C'*, which is adapted to open and close the upper end of the pipe *C*, while the valve or damper *C²* is arranged below the horizontal portion of the pipe *C* and is adapted to open or close that portion of the pipe *C* which connects with the conduit *E*. At the outer end of the pipe *C* is arranged the blower *F*.

In the chamber *A²* is arranged a bunch of parallel tubes *A³*, the ends of which open into the chamber *D* and the header *D'*, respectively. The conduit *E*, one end of which opens into the header *D'*, extends the full length of the drier or kiln and is provided at intervals in its length with dampers *E'*, which are opened and closed by means of the rods *E²*, which extend through one side of the drier or kiln. A fire-box *E³* is arranged on the conduit *E* at the end of the drier.

The carrier in the drier or kiln is composed of cables *H*, having attached thereto at regular intervals the transverse strips *K*, which are adapted to hold the pallets *L*. The cables *H* are operated by the pulleys *H'* and are sustained at intervals by the rollers *H²*. The pulleys *H'* are rigidly attached to the arbor *J*, to one end of which is attached a gear-wheel *J²*.

The drier or kiln *N* is provided at intervals in its length with ventilators *N'*, which may be opened and closed at will, also with a ventilator or escape-chimney *N²*. *M* is the brick-machine and *T* the dump-table and are placed upon the drawings to indicate their approximate position in relation to the drier.

The hot gases and smoke from the fire under the boiler A are obliged to pass from the smoke-box A' into the chamber A² and circulate about the tubes A³ therein before it 5 can escape through the flue or chimney A⁴. The exhaust-steam, which is conducted from the engine through the pipe B⁴ into the chamber A³, together with the hot gases, heat the tubes A³ therein, and when it is necessary 10 live steam from the boiler may be turned into the chamber A² through the pipe B. The steam in the chamber A² prevents the soot from accumulating and forming a crust about the tubes A³ and also provides a draft through 15 the chamber. The damper A⁵ in the flue A⁴ is also adapted to regulate the draft.

The blower F can be propelled by any usual means and is arranged at the outer end of the pipe C to force the fresh air into the chamber 20 D through the tubes A³, where it is heated, into the header D', and thence into the conduit E, through which it passes into the drier. This object is accomplished by opening the upper valve C' and closing the lower valve C² 25 in the pipe C. Should it become necessary to have more heat in the conduit E, this can be provided by turning the live steam from the boiler through the pipe B² into the chamber D. This might be required at night or 30 such other times as the engine would not be running.

The heat in the different parts of the drier can be regulated by the dampers E' and can be arranged so that the heat in the center thereof is much greater than at either end. 35 This condition is advantageous, as the green bricks placed on the carrier at one end will be gradually carried into the higher temperature in the center and thence through a gradually-decreasing temperature to the opposite 40 end, where they are removed.

A collar or fire-box E³, of inflammable material, is arranged about the conduit E outside of the drier. Should the heat in the conduit E become so great as to endanger the drier, this fire-box will ignite and being in a position to be plainly seen by those about the plant will attract their attention.

Cold air can be forced into the conduit E 50 by means of the blower F by closing the upper valve C' and opening the lower valve C² in the pipe C.

The carrier extends the full length of the drier and is arranged above the conduit E. 55 It is composed of cables H, to which is attached the transverse strips K. These strips are in the form of an inverted T and are arranged at regular intervals on the cables H, so as to engage and hold the ends of the pallets L, upon which the bricks are dumped as they come from the mold. These pallets are to be placed side by side on the cross-pieces 60 and may be piled any number of tiers high.

The cables H, with the cross-pieces K thereon, are operated by the pulleys H', which are rigidly attached to the arbor J. A gear-wheel J² is arranged at one end of the arbor

J and may be of such character as is best adapted to be operated by the machinery in the plant. The cables H are adapted to move 70 on and be supported by the rollers H².

In operation the carrier is moved forward until one of the cross-pieces K is above and a little beyond the arbor J, where it is allowed to remain until the first row of loaded pallets is 75 placed thereon, when the power is applied to the gear-wheel J² and the carrier moved forward until the next cross-piece K assumes the position last described. Another row of loaded pallets can be placed thereon. This 80 can be continued until the carrier is full, when the dried bricks can be removed from the carrier at the opposite end and placed in the kiln-shed while the fresh bricks are being loaded. By this means it will be seen 85 that the green bricks are gradually advanced into and through the drier.

The drier and carrier may be made of any desired dimensions to correspond with the 90 capacity of the plant.

In the accompanying drawings four cables are shown; but I do not care to limit myself to that number, as more or less may be used to conform to existing conditions.

Ventilators N', which may be opened and 95 closed at will, are arranged along the side of the drier near the roof and, together with the escape-chimney N², provide means to further regulate the temperature in the drier.

By the foregoing arrangement and combination of parts a new and simple means is provided for gradually drying bricks, tiles, &c., in a pure heated air without any additional cost of operation.

Having thus described my invention, what 105 I claim, and desire to secure by Letters Patent, is—

1. A drying-kiln having at one end a chamber in which the products of combustion together with the exhaust-steam are utilized to 110 heat a bunch of tubes therein, a series of tubes in said chamber, a header into which the heated air from the tubes is discharged, a conduit to transmit the heated air in the header into the kiln, and means to force the 115 air through the tubes into the header and conduit, substantially as described.

2. A drying-kiln having at one end a heating-chamber through which the hot gases and smoke are arranged to pass, a smoke-box 120 opening into said chamber, a flue through which the smoke escapes from said chamber, a damper arranged in said flue, a series of tubes arranged in said chamber, a header into 125 which the heated air from the tubes is discharged, conduits to convey the heated air from said header into the kiln, a series of dampers in said conduits, a system of pipes and valves, whereby either live or exhaust steam or both may be utilized in connection 130 with the products of combustion in the heating-chamber, a blower adapted to force the air through the tubes in the heating-chamber into the header and conduits, a blower-pipe

connected with said conduits, a system of valves in said blower-pipe whereby cold air may be forced into the conduit, and a fire-box arranged on the outer end of said conduit, substantially as described.

5 3. A drying-kiln having at one end a chamber in which the products of combustion are utilized in conjunction with the exhaust steam in heating a bunch of tubes therein, a series of tubes arranged in said chamber, a header into which the heated air from the tubes is discharged, a means to transmit the heated air from the header into the kiln, and means to force the air through the said tubes 10 into the header, an endless carrier arranged in said kiln above the heater, and means to propel said carrier, substantially as described.

15 4. A drying-kiln having at one end a heating-chamber through which the hot gases and smoke are arranged to pass, a smoke-box opening into said chamber, a flue through which the smoke escapes from said chamber, a damper arranged in said flue, a series of tubes arranged in said chamber, a header into 20 which the heated air from the tubes is discharged, a conduit adapted to convey the 25

heated air from the header into the kiln, which conduit is provided with a series of dampers within said kiln, a system of pipes and valves whereby either live or exhaust 30 steam or both may be utilized in conjunction with the products of combustion in the heating-chamber, a blower adapted to force the air through the tubes in said chamber into the header and conduit, a blower-pipe having 35 a system of valves therein whereby cold air may be forced into the conduit, a fire-box arranged on the conduit outside of the kiln, an endless carrier composed of cables to which transverse platforms are attached at intervals, an arbor having pulleys rigidly attached thereon and adapted to propel said cables, means to revolve said arbor, rollers adapted 40 to support said cables, and ventilators at intervals in the length of said kiln, substantially as described.

In testimony whereof I affix my signature in presence of two witnesses.
